UNITED STATES PATENT OFFICE.

JOHN W. MEAKER, OF CHICAGO, ILLINOIS, AND WILLIAM P. GLEASON, OF GARY, INDIANA.

FENCEPOST.

Application filed February 1, 1924. Serial No. 689,976.

This invention relates to a new and improved fence post and more particularly to a metal post and to such a post provided with integral means adapted to restrain 5 movement of fence wires vertically of the post.

A metal fence post in order to be commercially practicable must be formed with a cross section providing very considerable resistance to flexure without excessive weight. 10 Excessive weight not only increases handling cost but materially increases the cost of the post itself since the cost is directly based upon the weight of metal in the post. 15 It is particularly necessary that the post have stability in a direction normal to the line of the fence which the post supports. The greatest stresses which the post must resist will take effect in this direction and 20 moreover stresses along the fence line will be distributed between adjacent posts by the fence wires.

Fence wires are normally secured to posts of this character by means of wires, clips or 25 ties, and it is essential to provide means for preventing movement of the wires and ties vertically of the post. Further, with usual types of T-shaped or L-shaped posts, it is necessary to bend the securing clips around 30 relatively sharp edges which have a tendency to shear the clips if bent down with a sharp blow.

It is an object of the present invention to provide a new and improved metal fence 35 post having a T-shaped cross section and provided with a bulb upon the leg of the T so as to provide a maximum strength against normal bending stress with a minimum of material.

40 It is a further object to provide a metal fence post which has formed therein means for preventing vertical displacement of fence wires, said means being operative regardless of the portion of the post engaged by 45 the wire.

It is also an object to provide a post adapted to retain in place wire engaging 50 clips and to provide rounded surfaces engaging said clips.

55 It is an additional object to provide a post construction adapted for commercial production by the rolling process.

Other and further objects will appear as the description proceeds.

We have illustrated a preferred embodiment of our invention in the accompanying drawings, in which—

Figure 1 is a face view of the post;

Figure 2 is a fragmentary perspective view 60 on an enlarged scale;

Figure 3 is a section taken on line 3—3 of Fig. 2;

Figure 4 is a section taken on line 4—4 of Fig. 2; and

Figure 5 is a section taken on line 5—5 65 of Fig. 3.

As best shown in Figure 2, the post is formed T-shape in cross section having the web or leg of the T 5 provided upon its edge with the bulb 6. The web 5 is joined to the cross of the T or flange 7 by fillets 8. The edges of the flange 7 are formed in the rolling process to provide spaced serrations having the high points 9 and the low points 10. The serrations extend to the rear face of the flange 7 and the portions 11 opposite the low points 10 extend beyond the rear face of the web. The recesses or depressions 12 are formed opposite the high points 9. It will be noted that the entire front surface of the serrations is located in advance of the central flat face 13 of the flange 7, the depressed portions or low points 10 being materially in advance of the surface 13 as clearly shown in Figure 3.

As shown in Figure 1, the post is pointed at 14 upon its lower end and may be provided with the holding spade 15 which has turned up flanges 16 secured to the web 5 by means of rivets 17. The form of spade 90 shown is provided with the bent-up portions 18 which aid in retaining it in the ground.

As shown in Figure 2, a wire 19 may rest adjacent the low portions 10 of the serrations and be held in position by a clip 20, the rear end 21 of which may be bent around the rounded surface of the bulb 6 to retain the clip and wire in place. When so located, the wire engages only the edge serrations 100 and does not contact with the surface 13.

It will be noted that the high places and low places in the serrations upon the two edges of the flange are respectively opposite each other. These serrations are spaced so that there is but a relatively short distance between adjacent low spots 10 and the serrations extend throughout the full height of

the post so that the wire may be retained in place at any point throughout the height of the post.

The fact that the serrations are above or 5 in advance of the flat face of the post throughout their extent causes the fence wire to be held out of contact with the flat face regardless of the vertical position of the wire. The wire is thus not held too tightly 10 against longitudinal movement and may slip under stress sufficiently to yield and avoid rupture of the wire or fence. The fact that the serrations extend to the rear aids in preventing slipping of the wire retaining clips. 15

15 The metal of the post is so distributed about the neutral axis as to give very high resistance to bending in the direction parallel to the web of the post. It is in this direction that the maximum stresses may be 20 expected. The post as stated is preferably provided with a spade in order to give adequate bearing against the ground to support stress in this direction. The web itself serves to give adequate anchorage against dis- 25 placement in the direction normal to the web since this direction is parallel to the fence line where but small stresses are to be ex- pected and where adjacent posts support each other by means of the fence.

25 We claim:

1. A metal fence post or the like T-shaped in cross-section and having a flat face and serrations along an edge of the face, said serrations having relatively narrow wire en- 30 gaging portions and extending to the rear

of the face whereby vertical displacement of wire engaging clips is prevented.

2. A metal fence post or the like, T-shaped in cross section and having a flat face, serrations along both edges of the face adapted 40 to prevent vertical displacement of the wire, the serrations having relatively narrow wire engaging portions and extending beyond the face throughout their extent whereby fence wire may be maintained out of contact with 45 the face and extending to the rear of the face whereby vertical displacement of wire engaging clips is prevented.

3. A metal fence post or the like, T-shaped in cross section and provided with a bulb 50 formed at the bottom of the leg of the T, said post having a flat face and serrations along both edges of the face, the high and low points of the two series of serrations being similar and opposite each other whereby 55 wire may be engaged at spaced points to prevent vertical displacement thereof, the serrations having relatively narrow wire en- gaging portions and being beyond the flat face throughout their extent whereby fence 60 wire is maintained out of contact with the post face, and the bulb serving as a rounded surface about which to bend a wire engaging clip.

Signed at Chicago, Illinois, this 14th day 65 of January, 1924.
